UNITED STATES PATENT OFFICE.

MICHAEL B. GREEN, OF MEMPHIS, TENNESSEE.

OIL-PRESS.

1,194,997.

Specification of Letters Patent. Patented Aug. 15, 1916.

Application filed April 4, 1916. Serial No. 88,903.

To all whom it may concern:

Be it known that I, MICHAEL B. GREEN, a citizen of the United States, residing at Memphis, in the county of Shelby and State 5 of Tennessee, have invented new and useful Improvements in Oil-Presses, of which the following is a specification.

This invention relates to oil presses and more particularly to the boxes and mats 10 used in connection therewith.

As is well known, the old process of pressure by extraction using the old style hair mat has great advantages in point of quantity of oil expressed, owing to the porous 15 character of such mats whereby maximum expression is allowed. Such method of extraction, however, is slow and expensive, and in order to overcome this objection it has heretofore been proposed to use mats in the 20 form of perforated metal plates. This perforate plate method is much more rapid and much less expensive than the hair mat method, but objectionable on account of less yield, due to deficient porosity, and to liability 25 of distortion of the plates under pressure.

In my prior Patents No. 1,061,839, dated May 13, 1913, and No. 1,081,905, dated Dec. 16, 1913, and in my prior application Ser. 30 No. 50,058, filed Sept. 10, 1915, I have disclosed mats of a construction which combine to a large extent the qualities of porosity and yielding capacity of the hair mat with the working space of the perforate plate 35 mat, and which, at the same time, are free from the aforesaid objections to mats of the character referred to.

The present invention appertains to metallic mats and boxes of the general character 40 set forth in my aforesaid patents and application, and has for its object to provide devices of this character which, like my aforementioned devices, are designed to secure maximum expression of oil with speed 45 of action, and to also provide means for improving the porosity of the mats and boxes and facilitating the drainage off of the oil as expressed.

The present invention further has for its 50 object to provide a construction which enables a maximum number of boxes and mats to be used in a given size of press thus increasing the capacity of the press; which simplifies the construction and increases the 55 drainage capacity of the mats while affording maximum strength and resistance to

distortion; and which secures a better guiding and supporting action to prevent displacement or canting of the mats and displacement of the cake from between the 60 crushing surfaces.

With these and other objects in view, the invention consists of the features of construction, combination and arrangement of parts hereinafter fully described and 65 claimed, reference being had to the accompanying drawings in which:—

Figure 1 is an elevation of an oil press embodying my invention with a number of the boxes in section. Fig. 2 is a top plan 70 view of one of the mats. Fig. 3 is a longitudinal sectional view through the same. Fig. 4 is a fragmentary cross sectional view on an enlarged scale. Fig. 5 is a fragmentary corner view of some of the mats illustrating the manner of suspending and slidably connecting the same. Fig. 6 is a detail 75 sectional view thereof.

To illustrate the invention I have shown an ordinary oil press consisting of a base 1, 80 corner posts or uprights 2, a head 3 carrying a base plate 4, which receives the thrust of the boxes as they are propelled by the ram, the plunger 5 of which only is shown.

Slidably suspended upon bolts 6 are boxes 85 which consist of a plurality of what may be termed base plates 7, each of which may be corrugated upon its under surface, as shown at 8, and which is secured, as by means of screws 9 to the mat 10, having upwardly 90 projecting guide flanges or plates 11, adapted to slidably receive and engage the base plate and mat of the next adjacent upper box. More correctly speaking, the box consists of the undersurfaces of one base plate, 95 the mat supported upon the next lower plate, and the guiding flanges 11 upon such mat. The cakes from which the oil is to be expressed are spaced upon the surfaces of the mats and squeezed between the mats and 100 coöperating base plates, by the movement of the boxes upward into collapsing relation under the action of the hydraulic ram, as will be readily understood. The oil expressed in the operation of the press is dis- 105 charged, partly by drainage off the ends of the mats into a suitable receiving trough, not shown, and partly through the perforated mats, the oil descending from box to box and being discharged from the final or 110 lowermost box of the series into a suitable receptacle or into the aforementioned trough,

as will be readily understood. I have not considered it necessary to enter into detail about the construction and arrangement of the oil receptacles, as these constitute no part 5 of the present invention.

Each mat comprises a series of longitudinal parallel intermediate bars 12 and outer or side bars 13, which bars have their contiguous side edges arranged in abutting 10 relation, and all the bars of the series being fastened to the base plate 7 by the screws 9 and to each other by means of transverse rivets 14 or other suitable fastening means. The upper surfaces of the bars are transversely corrugated to form oil receiving 15 depressions 15 and produce a crushing surface which co-operates with the corrugated surface of the coacting base plate 7.

The meeting faces or sides of the bars are 20 formed with semi-elliptical grooves 16, which co-operate to provide longitudinally extending oil discharge channels 17, opening through the ends of the mat. Formed in the upper surfaces of the bars are vertical 25 transverse slots or slits 18 which open through the corrugated face of the mat. These slits or slots are arranged in transverse series, on opposite sides of the longitudinal center of each bar, the slots of each 30 series being staggered with respect to or alternating in arrangement with the slots of the other series, and the slots of adjacent bars being staggered with respect to or alternating in arrangement with each other. 35 This construction provides the corrugated surface of the mat with drain channels of which a maximum number may be employed and which will afford a maximum extent of aggregate perforated surface giving 40 a maximum range of porosity or drainage capacity to the mat, without weakening or impairing the strength and rigidity of the mat bars. The slots extend down through the overhanging portions of the 45 walls of the grooves 16 and communicate with said grooves for the conduction of the oil thereto, so that the large channels 17 may carry off or discharge the oil with ease and facility.

50 For the purpose of further increasing the drainage capacity of the mat, the meeting edges of the bars are cut away or spaced slightly to provide longitudinal drain channels 19, and below the surfaces forming 55 these channels the side faces of the bars above the grooves 16 are formed with inclined surfaces 20 diverging downwardly and progressively widening the slots 20 to insure the rapid passage of the oil to the 60 channels 17 and to prevent any liability of clogging or choking of the slots. Still further drainage capacity is afforded by providing the surfaces 20 with recesses or indentations 21, providing auxiliary clearance 65 channels along the walls of the slots 19, as

will be readily understood, by which means any particles of the oil cake which may pass downward with the oil will be prevented from clogging in or gumming up the longitudinal drain passages or tending to clog 70 the transverse drain slots. Flaring or conical auxiliary drain passages 22 are also formed in the overhanging walls of the grooves 16, said sockets or nozzles having their reduced or restricted ends communicating 75 with the transverse slots and their widened ends communicating with the grooves, so as to further and additionally provide for the free drainage off of the oil. These passages also provide for the use of 80 a steam blast device composed of slotted tubes which may be fitted within the channels 17 and employed for the purpose of injecting blasts of hot steam upward through the slots for the purpose of clearing the 85 same of any obstructions and cleaning the same at intervals in a ready and convenient manner. It will be observed that the drain slots have their inner walls inclined downwardly and outwardly at an angle to the 90 channel forming grooves, thus imparting to each slot a substantially V-form, whereby the discharge of oil and particles of cake will be facilitated, owing to the natural shedding action by gravity of the walls of 95 the slot.

The side bars 13 of the mat are provided with outwardly extending horizontal flanges 23, each provided at its respective ends with series of openings 24. Through some of the 100 openings at each end of each flange pass bolts 25 detachably securing to the flange a bracket 26, and the respective brackets 26, which are thus arranged adjacent to the corner portions of the mat, are provided with slotted or bifurcated guide members 27 slidably engaging guide rods or bars 28 fitted in key ways or grooves in the corner posts 2 of the press frame, whereby each mat is slidably mounted for vertical motion. The mats are 110 supported and suspended from the head portion of the press frame and from each other by the bolts 6, which engage certain of the other perforations 24, and each of these bolts is rigidly connected with a flange of one of 115 the mats and slidably engages the flange of the next adjacent mat, the series of bolts throughout being staggered in arrangement, so that the mats may move upwardly in collapsing relation without interference between 120 their guiding connections, the mode of mounting described also permitting the mats to be removed and reapplied in a ready and convenient manner. The guide flanges 11 project upwardly from the flanges 23 of the 125 side bars 13, and the flanges of each mat are adapted to encompass and ride in guided connection with the base plate and bars of the next adjacent upper mat and form therewith a compression box, as will be readily under- 130

stood, such action applying except in the case of the uppermost mat the bars and flanges of which coöperate with the upper stationary plate 4 on the head portion of the press frame. It will be evident that by the described mode of mounting the mats each mat will be firmly and securely supported, and during the compressing action the flanges 11, by running in guided engagement 5 with the box forming portion above, will maintain the mat in a true horizontal position and prevent it from tilting or canting and at the same time serve as guards to prevent the oil cake from escaping at the sides 10 of the mat and dropping down without being subjected to compression, evenness of compression and an avoidance of waste of material being thereby secured.

From the foregoing description, the construction and operation of the press will be readily understood, and it will be seen that the invention provides a construction of mat which will be firmly supported and guided in its movements with the stated resultant 20 advantages. It will also be seen that by the construction described the porosity or drainage capacity of the mat will be greatly increased over prior constructions of metallic mats, by which the expressing quality of the 25 ordinary hair mat will be simulated to a very high degree, together with the quickness of operation of the perforated metallic mat, while avoiding the well known objections to mats of these classes. Furthermore, the 30 construction described allows the drain passages in the mats to be blown out and relieved of adhering material with great convenience 35 and facility.

Another and important advantage of my 40 invention resides in the fact that by making each mat of a single base plate or apron and compression bars directly secured thereto, much space is saved over structures employing a base plate in addition to the apron to 45 which the bars are attached, the aggregate space then being sufficient in a press of the capacity of, say, fourteen boxes, to enable an additional box to be employed, thus increasing the capacity of the press.

50 I claim:—

1. A mat for oil presses comprising bars having grooves in their meeting faces forming oil discharge channels, cut-away portions along the margins of their meeting edges 55 forming longitudinal drain passages communicating with the channels, transverse slots opening through their surfaces and lateral faces and communicating with the channels, and conical passages leading up-

wardly from the channels and intersecting 60 said slots.

2. A mat for oil presses comprising bars having discharge channels below their surfaces and transverse slots intersecting said channels, and also having conical passages 65 leading at an angle from the walls of the channels and intersecting said slots at points spaced from the lateral faces of the bars.

3. A mat for oil presses comprising bars having grooves in their meeting faces forming oil discharge channels, slots opening through their upper surfaces and side edges and communicating with said channels, cut 70 away portions along the margins of their meeting edges forming passages communicating with the channels, and notches or recesses formed in the walls of said marginal portions.

4. A mat for oil presses comprising bars having grooves forming discharge channels 80 below their surfaces, transverse slots intersecting said channels, and conical passages extending upwardly and inwardly at an angle from the inner walls of the channels and intersecting the slots at points inward from 85 the lateral faces of the bars.

5. A mat for oil presses comprising bars having grooves in the meeting faces thereof forming oil discharge channels, cut-away portions along the margins of their meeting 90 edges above the channels providing longitudinal drain passages communicating with said channels, transverse slots opening through the surfaces and lateral faces of the bars and communicating with said longitudinal 95 drain passages and channels, and conical passages extending at an upward and inward angle from the inner walls of the channels and intersecting said transverse slots at points inward from the lateral faces of the 100 bars.

6. A mat for oil presses comprising bars having grooves in their meeting faces forming oil discharge channels, slots opening through their upper surfaces and side edges 105 and communicating with said channels, cut away portions along the margins of the meeting edges of the bars forming passages communicating with the channels, notches or recesses formed in the walls of said marginal 110 portions, and conical passages communicating at their bases with said grooves and extending at an angle through the bars and having their reduced ends intersecting the slots at points inwardly from the meeting 115 faces of the bars.

In testimony whereof I affix my signature.

MICHAEL B. GREEN.
